UNITED STATES PATENT OFFICE

ARBA G. WILLIAMSON, OF CARNEGIE, PENNSYLVANIA, ASSIGNOR TO THE UNION SWITCH & SIGNAL COMPANY, OF SWISSVALE, PENNSYLVANIA, A CORPORATION OF PENNSYLVANIA

TRAIN CONTROL SYSTEM

Original application filed November 10, 1926, Serial No. 147,403. Divided and this application filed November 14, 1930. Serial No. 495,724.

The present invention relates to train-control systems, the train or traffic controlling means being of any suitable character such as signals or retarding or stopping devices or both, and has for its main object and feature the employment of a gas-containing electron discharge device on the train controlled by a track-circuit and controlling the signals or other devices carried by the train.

10 This application is a division of application Ser. No. 147,403 filed November 10, 1926.

In the accompanying drawing the invention is disclosed, by way of illustration but not of limitation, in a concrete and preferred 15 form, of which

Fig. 1 is a diagrammatic view of a track circuit that may be employed in connection with the invention;

20 Fig. 2 is a diagrammatic view of a train-carried equipment disclosing one form of the invention; and

Fig. 3 is a graph showing a characteristic curve of a gas-containing electron tube.

Carried by the train is a traffic-governing 25 relay 24 which may be biased in any of the ways known in the art, such as those disclosed in application Ser. No. 147,403 previously referred to, to assume one condition when current of an intermediate value (for instance an average value of 0.40) is flowing 30 through its coils, and to assume another condition when current is either increased (as to the value of 1.00) or decreased with respect to said intermediate value. In the present case, relay 24 is provided with a neutral 35 armature 28 that remains in its up position so long as current of an intermediate or of greater value is flowing in the coils of 24, and that drops when current is absent or falls 40 below said intermediate value. Relay 24 is further provided with a polarized armature 30 that assumes a right hand position (as viewed in Fig. 2) as long as current of an intermediate value is flowing in the coils of 45 24, and that assumes a left hand position when the current flow in the coils of 24 is either increased or decreased with respect to said intermediate value. Carried by the train is also a gas-containing electron discharge 50 device or tube E which acts as a detector and

which is provided with a plate P³, a grid G³ and a filament F³. The gas or vapor contained in the tube may be of any suitable character such as sodium, potassium or an alloy thereof.

The pick-up or receiving circuit consists of the pick-up coil 1, wire 220, grid G³, filament F³ and wires 213 and 219 back to coil 1. A tuning condenser 222 spans the wires 219 and 220. The filament is heated by battery 211 connected by wires 212 and 213 to the filament F³. The plate circuit consists of battery 216, wire 217, relay 24, wire 218, plate P³, filament F³, and wires 213 and 215 back to battery 216. The circuit through the train controlling device or train indicating device 33 consists of battery 216, wire 217, neutral armature 28 of relay 24, polarized armature 30 of 24, wire 225, magnet of 33, and wires 226 and 215 back to battery 216.

It is well known that when traces of certain gases or metallic vapors are introduced into an electron tube, a larger flow of plate circuit current will result, and that by the proper choice of working values the operating effectiveness of the tube as a detector of electric current can be increased. The advantage of the use of such a tube is therefore that lower plate and filament voltages can be used, when the plate current grid-voltage characteristic curve is so selected that its curvature will result in greater effectiveness of the tube as a detector. In Fig. 3 is shown a characteristic curve for a tube containing sodium-potassium alloy vapor, and it will be noted that at its upper end the curve takes a sharp bend indicating the saturation point. N_s indicates the saturation point and this point is reached at zero grid potential with respect to the filament, and therefore any increase in the positive potential of the grid with respect to the filament does not increase the value of the plate current.

Let us assume that the parts are so arranged and the plate and filament voltages are so selected that, when no voltage is impressed on coil 1, the operating point on the curve of Fig. 3 is N³. Then when an alternating current is induced in coil 1 the voltage applied to the grid during the positive half

cycle ($+e$) will not increase the flow of current in the plate circuit but when the negative potential is applied to the grid during the negative half cycle ($-e$) the flow of current in the plate circuit will be materially reduced, the reduction being indicated by i_2 . Thus an intermediate value, say 0.40 will be established when current is present in the track circuit, whereas when no current is present in said track circuit the value of the current in the plate circuit will increase.

Therefore when no current is induced in coil 1 and the pick-up circuit, the value of the current in the plate circuit is 1.00, but when current is so induced the average value of the current in the plate circuit is 0.40.

The result is that whenever current is present in the track circuit the train controlling circuit through magnet 33 is closed, and whenever current in the track circuit is absent the train controlling circuit through magnet 33 is open. Furthermore, if for any reason the source of current on the train fails or a circuit becomes so disarranged that tube E fails to properly function and the plate current falls to a low value or to zero, this condition is indicated by the circuit through train controlling magnet 33 being ruptured by the polarized armature and also by neutral armature 28.

As shown in Fig. 1, 55 and 56 represent the two traffic rails arranged into blocks A, B and C by means of insulation 3'. The normal direction of traffic through said blocks is indicated by the arrow between the rails. At the ingoing end of each block is a relay, marked 148 in block C and 148' in block B, connected across the rails by suitable leads, and at the outgoing end of each block in a track battery 155 which is connected across the rails by leads 150 and 156. The function of this battery is merely to energize a track relay like 148'—it is not sufficiently powerful to control the train. The train control current is here supplied from generator 51, in this instance of the alternating current type, by way of line wires 52 and 53 to a track transformer associated with each block. Taking block B as an example, it will be seen that the primary of track transformer 101 is connected by wires 143 and 144 to line wires 52 and 53. Secondary 145 of the track transformer is connected to rail 56 by wire 146, armature 147 (of the track relay of the block in advance) contact 149 and wire 150, and is connected to rail 55 by wire 152, resistance 153 and wires 154 and 156. The function of resistance 153 is to prevent secondary 145 from short circuiting the battery. An impedance coil 157 is interposed in wire 156 to choke back the flow of alternating current so that it will not pass to the battery. The power supplied from secondary 145 to the rails is of such amplitude that the pick-up circuit on the train will be energized. It

will now be understood that the presence, in the rails, of current from 145 will choke down the current in the train-carried charged circuit so that it will have the intermediate value of 0.40, and therefore the circuit under control of relay 24 will remain closed.

If block C be unoccupied, then track relay 148 will be energized and train-control current from secondary 145 will pass to the rails of block B, with the result that if a train enters block B from block A, such train will have its cab equipment controlled thereby giving a clear indication. On the other hand if block C is occupied when a train enters block B from A, then such train, entering block B from A, will receive no train-control current because track relay 148 of block C will have been deenergized by the train in block C thereby dropping armature 147 and opening the circuit from secondary 145 to rails. The effect of this condition on the train is that a current value of 1.00 is established in the charged circuit passing through relay 24, and that therefore the circuit through 33 is ruptured.

It will further be observed that, although the presence of a train in block C deenergizes track relay 148 and thus cuts off train-control current from the rails of block B, track relay 148' of block B will nevertheless remain energized (provided B is unoccupied) by reason of current flow from battery 158 so that a train in block A will not be controlled by a train in block C.

If a train enters a block already occupied by another train, then the train so entering will be subject to no train-control current.

I claim:

1. A train control system including: a trackway circuit having a source of current, a train, a train-carried closed circuit having a source of current, a train-carried receiving circuit in an inductive relation with said track-way circuit and responsive to current flowing therein, and a train-carried gas-containing electron discharge device included in said receiving circuit and controlled thereby to establish a predetermined value of direct current flowing in the said closed circuit in response to a flow of current in the track-way circuit.

2. A train control system including: a trackway circuit having a source of current, a train-carried circuit in an inductive relation with said trackway circuit and responsive to current flowing therein, a train-carried charged circuit having a flow of current of a given value, and a train-carried gas containing electron discharge device controlled by the receiving circuit to lessen the flow of current in the charged circuit in response to a flow of current in the track circuit.

3. A train control system including: a trackway circuit having a source of current,

a train-carried pick-up circuit in an inductive relation to said trackway circuit and responsive to current flowing therein, a train-carried gas-containing electron discharge device, said device having a grid that is included in the pick-up circuit and that is rendered alternately positive and negative as long as current is induced in the pick-up circuit by current flow in the trackway circuit, and a train-carried charged circuit including the electron discharge device and having a flow of current of a given value, said value being decreased when the grid is rendered negative.

4. A train control system including: a trackway circuit having a source of current, a train, a train-carried gas-containing electron-discharge device having a plate, a grid and a filament, a train-carried closed circuit including the plate and filament, a low voltage source of current in said closed circuit to supply substantially its maximum flow when the voltage of the grid with respect to the filament is substantially at zero, and a receiving circuit on the train, including the grid and filament, in an inductive relation with said trackway circuit and responsive to current flowing therein to alternately render the grid positive and negative with respect to the filament whereby the flow of current in the closed circuit is substantially decreased below said maximum when the grid is rendered negative but not substantially increased above said maximum when the grid is rendered positive.

5. A train control system including: a trackway circuit having a source of current, a train, a train-carried electron-discharge device having a plate, a grid and a filament, a train-carried closed circuit including the plate and filament, a source of current in said closed circuit to supply substantially its maximum flow when the voltage of the grid with respect to the filament is substantially at zero, and a receiving circuit on the train, including the grid and filament, in an inductive relation with said trackway circuit and responsive to current flowing therein to alternately render the grid positive and negative with respect to the filament whereby the flow of current in the closed circuit is substantially decreased below said maximum when the grid is rendered negative but not substantially increased above said maximum when the grid is rendered positive.

Signed at Swissvale, in the county of Allegheny, and State of Pennsylvania, this 13th day of November, 1930.
